APPARATUS FOR APPLYING SIZING AND
OTHER COATINGS

Ralph A. Rusca, New Orleans, La., assignor to the
United States of America as represented by the
Secretary of Agriculture

Application August 5, 1949, Serial No. 108,836

2 Claims. (Cl. 28—28)

(Granted under the act of March 3, 1883, as
amended April 30, 1928; 370 O. G. 757)

1

This application is made under the act of March 3, 1883, as amended by the act of April 30, 1928, and the invention herein described, if patented in any country, may be manufactured and used by or for the Government of the United States of America for governmental purposes throughout the world without the payment to me of any royalty thereon.

This invention relates to an apparatus for coating or impregnating sheets, webs, or strands with sizing, polymerizable solutions or suspensions, and other coatings. It particularly relates to a size box for use in conjunction with the apparatus and method for drying textile warps described in an application filed by Ralph A. Rusca and George J. Kyame.

The customary apparatus for sizing and drying textile warps consists of: (1) a creel to support the section beams, (2) a size box for applying the starch solution to the yarns, (3) a dryer for evaporating the moisture from the impregnated yarns, and (4) a means for winding the dried yarn on a beam.

The slasher creel carries a number of section beams, each of which is wound with a plurality of yarn strands laid side by side in parallel alignment. The yarn strands are unreeled simultaneously from all section beams in a single sheet called the warp. The warp is guided into the size bath via an immersion roll and then over two size rolls which are more than half submerged in the bath. Mounted above each size roll is a heavy cloth-covered and weighted squeeze roll. These squeeze rolls subject the warp to a kneading action which increases the penetration of the size into the yarns and removes all excess size. The sized warp is then dried by means of a steam-heated cylinder dryer, or by means of a hot-air dryer. On leaving the dryer, the warp is separated into several sheets, as many as there are section beams supplying the yarn, by means of split rods, also called leese rods. This is done to separate those adjacent yarns which are stuck together with dried size. The separated sheets are reunited, passed through an expansion comb, and rewound on a beam. The purpose of the expansion comb is to appropriately distribute the warp yarns uniformly across the width of the beam and at the same time maintain their parallel alignment.

There are a number of disadvantages inherent in the methods and apparatus used heretofore.

In the sizing operation, the amount of size applied to the warp and the degree of penetration therein are both difficult to control because of

the fixed depth to which the warp is immersed in the size bath. Furthermore, to make effective the action of the squeeze rolls in increasing said penetration, it becomes necessary to have an excess of size present at the point of application of pressure. To accomplish this, the size rolls are partially submerged in the bath so that in turning they pick up and carry an excess of size to the zone of kneading action. Also, squeeze roll pressures conducive to effective kneading action are lower than those required for efficient removal of excess size from the warp. Therefore, while size penetration may be increased through regulation of squeeze roll pressure, it is found that effective kneading action is usually accompanied by inefficient removal of excess size. The partially submerged size rolls are always positively driven by means of their shafts, which extend through the side walls of the size box. This method requires the use of stuffing boxes to prevent leakage of size around the shafts, with the well known problems of maintenance of the stuffing box glands. The usual size box is rather large and box-like in shape and, with only three rolls in the box, there remains a considerable amount of unused space which must be filled with size, thereby adding to the difficulty of maintaining constant agitation and circulation of the contents. In the bottom of said size box is usually placed a coiled copper steam pipe, perforated with small holes to emit live steam into the size solution. The purpose of this is to maintain the temperature of the size solution in the box, and to assist in agitating the size and preventing its stagnation and stratification in the box. This continual flow of steam dilutes the size solution thereby adversely affecting the quality of the slashed warp.

To overcome these faults, this invention embodies the following features.

The size box is equipped with an immersion roll having a motor-driven means for regulating depth of immersion. The two size rolls are of unequal diameters and are driven at the same surface speed. This arrangement affords better control over size penetration and excess size removal in that, by regulating the level of size in the box so that it contacts only the larger diameter roll, this roll may be used for kneading the size into the warp, while the smaller diameter roll is used solely for removing the excess size. Or, if so desired, the size level may be raised to such height that the box functions in the same manner as in the prior art. A novel form of bearing mount and drive for the size rolls obviates

going through the size box walls and eliminates the stuffing boxes and their attendant problems. The size box is contoured to fit closely to the immersion and size rolls, thereby reducing the overall volume and increasing the agitation and circulation of the contents.

The drawings disclose one embodiment of my invention.

Figure 1 is a vertical view of the size box.

Figure 2 is a top view.

Figure 3 is a section on line 3—3 of Figure 2.

The size box 1 is supported by a suitable structural framework 2. An outer sheet-metal covering 3 and inner covering 30 attached to the same framework enclose a layer of insulating material 4, such as mineral wool, rock wool, or asbestos. Mounted atop framework 2, alongside the deeper end of box 1, is an idler roll 5 which guides the warp 75 as it enters the size box. An immersion roll 6 is suspended in the deep end of size box 1 by means of two threaded rods 7. Said immersion roll 6 rotates in suitable bearings 8 held in blocks 9 which are fixedly attached to the end of threaded rods 7. Blocks 9 are restrained against lateral motion by guides 10 and the side walls of box 1. Vertical displacement and positioning of immersion roll 6 is governed by rotation of worm gear 11. The latter has a threaded bore 111 into which rod 7 threads. Gear 11 is rotatably mounted in a housing 12 and is driven by worm 13, which is rigidly mounted on shaft 14. Shaft 14 is rotatably mounted in bearings 15 and is driven through pulley 16 by means of motor 160, having suitable controls.

Suspended in the shallow portion of the size box are two size rolls 17 and 18 respectively. Said size rolls are rotatably mounted in special hanger mountings 19 and 20, and operate in journal bearings 21 made of self-lubricating or water lubricating materials such as lignum-vitae, 40 plastic, and the like. Size rolls 17 and 18 differ in diameter but are driven at the same peripheral speed by sprockets 22 and 23, which have a teeth ratio equal to the ratio of the respective size roll diameters. Sprockets 22 and 23 are linked with sprocket 24 and receive their motive power therefrom by a chain 25. Sprocket 24 is mounted on one end of jackshaft 26, which is rotatably supported in pillow blocks 27. On the other end of shaft 26 is mounted sprocket 28, which is driven by sprocket 29 through chain 130. Sprocket 29 is mounted on countershaft 31, which rotates in pillow blocks 32. Countershaft 31 receives its motive power through sprocket 33, which is driven by suitable means not shown. Mounted directly above and in contact with size rolls 17 and 18 are two cloth-covered metal squeeze rolls 171 and 181 respectively. Both squeeze rolls are the same in diameter and are loaded by springs, 190 and 191 by means of hand wheels 200, or by any other suitable means, such as weighted levers, or hydraulic, or pneumatic pistons. A drain pipe 34 attached to the lowermost part of size box 1 is used to draw off the fluid contents of the box when necessary.

In operation, all warp yarns are unreeled simultaneously from the section beams on the slasher creel and passed in a single sheet 75 over idler roll 5 and into the size bath via immersion roll 6. The depth of immersion of the warp into the size bath is determined by the location of immersion roll 6 therein. The latter may be positioned by energizing the motor to drive pulley 16 in the direction necessary to raise or lower rods 7 as desired. From immersion roll 6, the warp 75

is passed between rolls 17 and 171 and then between rolls 18 and 181. Size roll 17 is larger in diameter than size roll 18. By suitably adjusting the level of size in size box 1, size roll 17 may be practically submerged in the bath while roll 18 still rides clear. This arrangement allows roll pair 17 and 171 to be used solely for kneading size into the warp thereby achieving maximum size penetration; coacting roll pair 18 and 181 remove all excess size from the surface of the warp. If conventional sizing action is desired, it is necessary only to raise the level of the size until both rolls 17 and 18 are partially submerged therein.

The size box is formed to fit closely to the various rolls it contains. This design results in considerable reduction in the volume of size required to fill the box, and movement of the warp and rotation of the rolls therein insures adequate agitation and circulation of the size. Thus, the need for live steam with its detrimental dilution of the size bath is done away with insofar as agitation of the size is concerned. The temperature of the size bath may be maintained by any of the conventional methods, such as steam coils, steam jacket, and electric heaters. However, I prefer to use the method described by me in a co-pending patent application, Serial No. 64,068, filed December 8, 1948, now Patent No. 2,516,884, entitled "Method of and Apparatus for the Preparation and Distribution of Sizing Materials."

Having thus described my invention, I claim:

1. A size box comprising a housing adapted to contain a body of liquid, the housing having a deep end and a shallow end, a submersible roll in the deep end mounted transversely of the housing and mounted for raising and lowering therein, two size rolls in the shallow end mounted transversely of the housing, the contour of the bottom of the housing in the shallow end following adjacent a side and bottom of one size roll and the bottom of the second size roll, the second size roll being adjacent the inlet of the shallow end, the contour of the housing in the deep end following adjacent the submersible roll in its fully lowered position, the diameter of each size roll being sufficiently large to fill the major part of the depth of the housing in the shallow part and a squeeze roll mounted above each of the two size rolls, the shallow end being provided by raising the bottom of the housing toward one end, the size rolls being mounted adjacent the top of the housing above the level of the submersible roll in its fully lowered position.

2. A size box comprising a housing adapted to contain a body of liquid, the housing having a deep part and a shallow part, the bottom of the housing being raised and sloping upwardly toward one end to provide the shallow part, a submersible roll in the deep part mounted transversely of the housing and mounted for raising and lowering therein, a large size roll mounted transversely of the housing in the shallow part adjacent the inlet of the shallow part, a squeeze roll mounted above the large size roll, the diameter of the large size roll being such as to fill the major part of the liquid depth of the housing at that point, a smaller size roll mounted transversely of the housing in the shallow part and adjacent the side of the housing and filling the major part of the liquid depth of the housing at that point, the lower edge of the smaller size roll being above the lower edge of the larger size roll, a second squeeze roll mounted above the smaller size roll, means for driving the two size

rolls at the same surface speed, the two size rolls and the submersible roll being supported by suspending means mounted above the liquid level, the two size rolls being above the level of the submersible roll in its fully lowered position, 5 the contour of the bottom of the housing in the shallow end following adjacent a side and bottom of the smaller size roll, and adjacent the bottom of the second size roll, the contour of the housing in the deep end following adjacent the submersible roll in its full lowered position, whereby the need for agitating means is obviated, the movement of the material that is being impregnated and the rotation of the rolls insuring adequate agitation and circulation of liquid.
